UNITED STATES PATENT OFFICE.

CHARLES ALMY, JR., OF CAMBRIDGE, MASSACHUSETTS, ASSIGNOR TO DEWEY & ALMY CHEMICAL COMPANY, OF CAMBRIDGE, MASSACHUSETTS, A CORPORATION OF MASSACHUSETTS.

APPARATUS FOR SPREADING LINING MATERIAL ON COVERS.

Application filed February 17, 1925. Serial No. 9,821.

To all whom it may concern:

Be it known that I, CHARLES ALMY, Jr., a citizen of the United States of America, and resident of Cambridge, in the county of 5 Middlesex and State of Massachusetts, have invented new and useful Improvements in Apparatus for Spreading Lining Material on Covers, of which the following is a specification.

10 The invention relates to apparatus for redistributing or uniformly spreading liquid lining material over the sealing area of can tops, covers and the like in order to obtain the most efficient sealing effect when applied 15 to the receptacle.

Objects of this invention are to provide a new and improved apparatus for distributing and uniformly spreading a liquid material of relatively low viscosity and plasticity over a selected area; to provide an apparatus particularly useful in redistributing liquid lining material over the sealing area of can tops, covers and the like in an even and uniform manner; and to provide an 25 apparatus of the above character having the unique features of construction and arrangement hereinafter described.

In the copending applications of Bradley Dewey and Theodore T. Miller Serial Nos. 30 9,823 and 9,826, filed on even date herewith there is shown and described an apparatus for distributing liquid lining material over can tops and the like. After the lining material is so distributed it is as a rule found 35 to be bunched near the outer edge of the cover, thereby militating against the desired air-tight connection when the covers are applied to the can bodies. According to the present invention the lining material is redistributed by means of an air nozzle which 40 directs an air current against the lining material on the covers in such a manner that the material is spread over a larger sealing area to form a regular coating of substantially uniform thickness throughout. Conveniently the covers may be rolled along a 45 track by a suitable conveyor arranged beneath the air nozzle so that as the covers are continuously rolled along the air current automatically functions properly to redistribute the material. Although I show a 50 preferred form of apparatus for distributing or applying the material to covers it is to be understood that other forms may be em-

ployed and I specifically do not intend to 55 be limited to the particular form shown except as specified in the appended claims.

In the drawings,

Fig. 1 is a side elevation of apparatus for 60 distributing liquid lining material on covers, and for redistributing the material over the sealing area;

Fig. 2 is a section on the line 2—2 o Fig. 1;

Fig. 3 is a fragmentary section of an air 65 nozzle and cover;

Fig. 4 is a top plan view of a cover with the lining material applied thereto;

Fig. 5 is a section on the line 5—5 of 70 Fig. 4; and

Fig. 6 is a fragmentary section of an air nozzle modified for can covers having a curled edge.

In the embodiment of the invention illustrated a depositor is of the form shown 75 and described in the above mentioned copending application, therefore a brief description of this apparatus is deemed sufficient in this instance. A depositor A comprises in general a rotating distributing roll 1 dipping into a bath 2 of liquid lining material and a smaller or regulating roll 3 spaced a suitable distance from the distributing roll and extending substantially parallel thereto. The rolls 1 and 3 80 are driven through suitable connections from a pulley 4, both rolls being driven in the same direction but the regulating roll 3 being driven in such a manner that the peripheral velocity thereof is less than that 85 of the distributing roll. As described in the aforesaid application, a track 5 extends substantially parallel to the distributing roll 1 on the side opposite from the regulating roll 3, and the covers X are rolled along the 90 track 5 with the peripheral edges thereof in contact with the surface of the distributing roll so that as the covers are rolled along the lining material flows or is scraped from the surface of the distributing roll to form 95 continuous rings on the covers. For rolling the covers X along the track 5 a conveyor B in the form of an endless cable is employed, the cable extending parallel to and at a proper distance from the distributing roll. The covers X preferably assume 100 inclined positions substantially as indicated in Fig. 2 and lie against the conveyor B at 105

5 a point between the center and the upper positions of their peripheries thereof so that by driving the cable the covers are continuously rolled along. For driving the cable sheaves 6 and 7 are employed over which the cable passes and a weighted sheave 8 maintains the cable taut, the sheave 6 being suitably connected to be driven from the pulley 4.

10 From the depositor A the covers X are propelled by the conveyor B to a track 9 of channel form in order to support the lower periphery of the covers and arranged above the track 9 is a distributor C which is preferably in the form of an elongate tubular nozzle having a slit 10 and a lower portion extending substantially the entire length thereof. By directing a gaseous fluid such as air through the inlet conduit 11 from 15 a suitable source such as a centrifugal blower the liquid lining material on each cover X which has been unevenly distributed circumferentially of the cover (Fig. 3) by the depositor A is spread over the sealing area of the cover in substantially a uniform manner as indicated in Fig. 5. It will be apparent that owing to the rolling action of the covers X along the track 9, the air current from the distributor C will 20 impinge against the lining material deposited on the cover throughout its circumferential margin and cause it to flow radially inward until it reaches the inner edge of the seal area or channel and to become uniformly disposed over the area thus 25 covered so that in this manner the effective sealing of the cover is materially increased.

30 The apparatus above described for depositing a liquid lining material on the covers and thereafter distributing lining material uniformly over the sealing area, is intended principally for use in connection with covers having an upstanding peripheral flange. Under some circumstances it may be desirable to crimp or curl the peripheral flange on the covers prior to the depositing and distributing of the liquid lining material, and in this case the lining material 35 may be deposited on the covers by any suitable means such as by a machine which rapidly rotates the covers under a nozzle which opens momentarily and squirts a measured amount of the material under the curled flange, such machine being at present in use universally. For distributing or 40 spreading the lining material uniformly over the sealing area a distributor C' of the form indicated in Fig. 6 may be employed, this distributor having an extension nozzle 45 50 55 60 65 70 75 80 85 90 95 100 105 110 115 120 125 130

Although the above described apparatus may be used beneficially with practically every kind of liquid lining material suitable for the purpose intended, it is particularly adapted to use liquid lining material having a relatively low consistency or viscosity as well as low plasticity. This kind of lining material has been found to be admirably adapted to the exigencies of this particular manner of sealing.

70 75 80 85 90 95 100 105 110 115 120 125 130

Although I have shown and described certain apparatus which is the best form known to me at the present time, it is to be understood that numerous changes in details of construction and arrangement may be effected without departing from the spirit of the invention, especially as defined by the appended claims. It is further to be understood that I do not limit the invention to the use of any particular kind of sealing compound, but may use any suitable compound adapted for the particular purpose, although it may prove necessary that certain minor details of construction and arrangement be changed.

I claim:

1. An apparatus of the character described comprising in combination a depositor for depositing liquid lining material on a cover, and a pneumatic distributor for spreading the thus applied deposit of liquid material over a selected area of the cover.

2. An apparatus of the character described comprising in combination a depositor for depositing liquid lining material on covers, a pneumatic distributor for spreading the material more uniformly over the sealing area, and a conveyor for successively moving the covers from the depositor to the distributor.

3. An apparatus of the character described comprising in combination a depositor for depositing liquid lining material on covers, a pneumatic distributor for spreading the material more uniformly over the sealing area, and a conveyor for rolling the covers successively from the depositor to the distributor in a continuous manner.

4. Apparatus of the character described comprising in combination a rotating depositing roll coated with liquid lining material, a conveyor for rolling the covers progressively along a longitudinal surface of said roll for depositing lining material on the covers, and a pneumatic distributor constructed and arranged subsequently to spread the thus applied deposit of liquid lining material uniformly over a greater area of the covers.

5. An apparatus of the character described comprising in combination a depositor for depositing liquid lining material on covers, a pneumatic distributor for subsequently spreading the thus applied deposit of liquid material in substantially a uniform manner

over a greater area of the covers, and means for continuously moving the covers in the region of said distributor.

6. An apparatus of the character described comprising in combination a depositor for depositing liquid lining material on covers, an air nozzle for uniformly spreading the thus applied deposit of liquid material over the entire sealing area of the covers, and means for continuously moving the covers relatively to the nozzle.

7. An apparatus of the character described comprising in combination a depositor for depositing liquid lining material on covers, an air nozzle for uniformly spreading the material over the sealing area of the covers, and a conveyor for rolling the covers delivered from the depositor relatively to said nozzle.

8. An apparatus of the character described comprising means for depositing lining material upon can covers, an elongate air nozzle, a track extending substantially parallel to the nozzle, and a conveyor for rolling the covers with lining material deposited there-

on along said track whereby the air current spreads the lining material over the sealing area of the cover in substantially a uniform manner.

9. An apparatus of the character described comprising means for depositing liquid lining material on a can cover having a circumferential groove, means for rotating the cover, and means for directing an air jet over the edge of the cover obliquely toward its axis thereby to distribute the material over the groove.

10. An apparatus of the character described comprising means for depositing liquid lining material on a cover in the form for sealing, means for rolling can covers along a predetermined path, and a nozzle disposed above said path for directing an air jet downwardly over the edge of the cover obliquely toward its axis thereby uniformly to distribute the material over a selected area.

Signed by me at Cambridge, Mass., this 11th day of February 1925.

CHARLES ALMY, Jr.
